UNITED STATES PATENT OFFICE.

HORACE L. FREEMAN, OF NEW YORK, N. Y., ASSIGNOR TO THE POST DATER STAMP CO., OF WILMINGTON, NORTH CAROLINA, A CORPORATION OF NORTH CAROLINA.

DATING-STAMP.

1,165,662.

Specification of Letters Patent. Patented Dec. 28, 1915.

Application filed June 14, 1915. Serial No. 33,885.

To all whom it may concern:

Be it known that I, HORACE L. FREEMAN, a citizen of the United States, and residing at New York, in the county of New York 5 and State of New York, have invented certain new and useful Improvements in Dating-Stamps, of which the following is a specification, such as will enable those skilled in the art to which it appertains to make 10 and use the same.

This invention relates to dating stamps, of the class shown, described and claimed in U. S. Letters Patent No. 1,086,851 and 15 1,086,852, granted February 10, 1914, and particularly to the endless carbon printing tape used in stamps of this class and means for operating the same, and the object thereof is to provide improved means of which the pivoted arm of the stamp forms a part 20 for reversing the movement of said tape at intervals.

In my improvement the printing tape consists of a carbon strip or sheet connected with two spools and adapted to be wound 25 from one spool onto the other in the operation of the stamp, and the invention described and claimed herein consists of improved means for automatically reversing the movement of the tape.

30 The invention is fully disclosed in the following specification, of which the accompanying drawings form a part, in which the separate parts of my improvement are designated by suitable reference characters 35 in each of the views, and in which—

Figure 1 is a sectional side view of my improved dating stamp with parts omitted; Fig. 2 a sectional plan view on the line 2—2 of Fig. 1; Fig. 3 a transverse vertical 40 sectional view on the line 3—3 of Fig. 2 and on an enlarged scale; Fig. 4 a vertical sectional view on the line 4—4 of Fig. 6; Fig. 5 a view similar to Fig. 4 but showing the parts in a different position; Fig. 6 a 45 sectional plan view of the constructions shown in Figs. 4 and 5; and, Fig. 7 a view similar to Fig. 4 but showing a modification.

In the drawing forming part of this specification, I have shown at *a* the casing and 50 at *b* the main pivoted operating arm of a dating stamp similar to that described in the patents hereinbefore referred to, and these parts including the spring *b*² by which 55 the arm *b* is operated in one direction and

the type disks *b*³, only one of which is shown, and other parts connected with the head *b*⁴ of the arm *b*, and connected with and operating in connection with the type disks, and means for operating the type disks and other 60 parts connected therewith are all the same as in the patents hereinbefore referred to and form no part of this invention and are therefore not shown and described in detail.

Mounted in the bottom rear back portion 65 of the casing *a* are two transversely arranged spindles *c* and *d* on which are mounted similar spools *e* and *f*, consisting of similar core pieces *e*² and *f*² provided at one end with disk-shaped heads *e*³ and *f*³ respectively.

Mounted on the spindles *c* and *d* and adjacent to the heads *e*³ and *f*³ of the spools *e* and *f* and rotatable on said spindles are disks *g* and *h* having upwardly directed arms *g*² 70 and *h*² connected by a horizontal link bar *i* on which is rotatably mounted a roller *i*² and the outer faces of the disks *g* and *h* are provided with transverse ribs *g*³ and *h*³.

The casing *a* of the stamp is provided 75 with side members *a*² and front and rear members *a*³, and the side members *a*² are provided with inwardly directed bosses *a*⁴ through which the spindles *c* and *d* of the spools *e* and *f* pass, and the bosses *a*⁴ of 80 the side *a*² adjacent to the heads *e*³ and *f*³ of the spools *e* and *f* are provided with transverse recesses *a*⁵ adapted to receive the ribs *g*³ and *h*³ of the disks *g* and *h*.

Rotatably mounted on the end portion of 85 the spindles *c* and *d* of the spools *e* and *f* opposite the head portions *e*³ and *f*³ of said spools are intermeshing gears *j* and *k* provided with outwardly directed hubs *j*² and *k*² and rigidly mounted on the hub *k*² of the 90 gear *k* is a ratchet *m*, and loosely mounted on the hub *k*² between the ratchet *m* and gear *k* is an arm *m*².

The main operating arm *b* is provided at or near its pivotal point *b*⁵ with a forwardly 100 directed ear or projection *b*⁶ to which is pivoted a rod *b*⁷, and the arm *m*² on the spindle *d* and the rod *b*⁷ are connected by a pivot pin *m*³ on which is mounted a pawl 105 *m*⁴ which operates in connection with the ratchet *m*.

The gears *j* and *k* are provided on their inner faces with clutch members *n* and *o*, and the adjacent ends of the core pieces 110 *e*² and *f*² of the spools *e* and *f* are provided

with corresponding clutch members n^2 and o^2 , and said adjacent ends of the core pieces e^2 and f^2 of the spools e and f are provided with central recesses p in which are mounted 5 springs p^2 which bear on the gears j and k . In the construction shown the recesses p and springs p^2 are shown only in the spool f but it will be understood that the spools e and f are both the same in this particular.

10 Mounted in the top portions of the casing forwardly and backwardly of the type disks b^3 are guide rollers r and r^2 , and mounted forwardly of and below said guide rollers is another guide roller r^3 and directly beneath 15 the type disk b^3 is another guide roller r^4 , and between the guide rollers r^3 and r^4 is a supplemental guide roller r^5 , and in the use of this stamp the printing tape or ribbon s is mounted on the guide rollers r , r^2 , 20 r^3 , r^4 and r^5 , or in connection therewith, as shown in Fig. 1, and the ends of said printing tape are connected with the spools e and f .

In the construction shown in Figs. 1, 2, 3, 25 4, and 6, the printing tape is shown wound on the spool e and ready to be re-wound on the spool f , as shown in Fig. 5. With the parts in this position the roller i^2 carried by the link bar i bears on the spool e on which 30 the printing tape is fully wound, and in this position the rib g^3 on the disk g is thrown into the corresponding recess a^5 , while the rib h^3 on the disk h is thrown out of the corresponding recess a^5 , as clearly shown in 35 Figs. 2 and 4, and in this position the clutch members o and o^2 are in engagement, while the clutch members n and n^2 are out of engagement, and the spool e is free to rotate on the spindle c . If now the arm b be successively depressed, as in the operation of 40 the stamp, the spool f will be rotated step by step and the tape s will be wound on said spool step by step until all the tape is withdrawn from the spool e and wound on the 45 spool f , as shown in Fig. 5, and in this operation the position of the link bar i and roller i^2 are reversed, and the roller i^2 bears on the spool f , or the tape wound thereon, and the position of the parts g and g^3 and 50 the parts h and h^3 are also reversed as are also the position of the clutch members m and m^2 and o and o^2 , and it must be understood that the springs p^2 in the spools e and f are instrumental in producing these operations. 55 As these springs move the spools e and f longitudinally on the spindles c and d in one direction, and when the disks g and h are in proper position the ribs g^3 and h^3 are forced into the corresponding recesses a^5 , and these parts also, as will be seen, operate as clutches.

60 From the foregoing description it will be seen that when the printing tape is being wound on one spool the other rotates freely on its spindle, and it is the operation of the

roller i^2 , the link bar i and the disks g and h that reverses the movement of the tape each time that it is fully wound on one of the spools, and this operation begins the rewinding of said tape onto the other spool. 70

As in the patents hereinbefore referred to the type disks b^3 are employed for printing the year, the month, and the day of the month, and name signature and other plates may be employed in the space or spaces t in 75 the top of the casing and at the sides of the type disks b^3 as in said patents.

In the construction shown in Fig. 7, the wheel or roller i^2 is made in the form of an eccentric or cam, and with this construction 80 the tripping movement which reverses the direction of the movement of the tape, or the direction of the rotation of the spools will be effected quicker than with the construction shown in Figs. 4 and 5, and other changes 85 in and modifications of the construction herein described may be made, within the scope of the appended claims, without departing from the spirit of my invention, or sacrificing its advantages. 90

Having fully described my invention, what I claim as new and desire to secure by Letters Patent, is:—

1. A dating stamp of the class described, comprising a casing, a main pivoted operating arm, two spindles mounted in the bottom portion of said casing below said arm, spools mounted on said spindles and movable longitudinally thereof, intermeshing gears mounted on said spindles adjacent to 95 one end of said spools, said gears and said spools being provided with clutch members, springs for throwing said clutch members out of engagement, and means whereby each operation of said arm will rotate one of 100 said spools in one direction.

2. A dating stamp of the class described, comprising a casing, a main pivoted operating arm, two spindles mounted in the bottom portion of said casing below said arm, 110 spools mounted on said spindles and movable longitudinally thereof, intermeshing gears mounted on said spindles adjacent to one end of said spools, said gears and said spools being provided with clutch members, 115 springs for throwing said clutch members out of engagement, means whereby each operation of said arm will rotate one of said spools in one direction, and other means whereby the movement of said spools will 120 be reversed at intervals.

3. In a dating stamp of the class described, a casing provided with a main operating arm and two parallel spindles, spools mounted on said spindles and movable longitudinally thereon and provided at one end with clutch members, intermeshing gears mounted on said spools and provided with corresponding clutch members, springs for moving said spools so as to throw said 125

130

clutch members out of engagement, and means whereby the operation of the main arm will rotate one of said spools.

4. In a dating stamp of the class described, a casing provided with a main operating arm and two parallel spindles, spools mounted on said spindles and movable longitudinally thereon and provided at one end with clutch members, intermeshing gears mounted on said spools and provided with corresponding clutch members, springs for moving said spools so as to throw said clutch members out of engagement, means whereby the operation of the main arm will 10 rotate one of said spools, and other means for reversing the operation of said spools at intervals.

5. In a dating stamp of the class described, a casing provided with a main operating arm and two parallel spindles, spools 20

mounted on said spindles and movable longitudinally thereon and provided at one end with clutch members, intermeshing gears mounted on said spools and provided with corresponding clutch members, springs for 25 moving said spools so as to throw said clutch members out of engagement, means whereby the operation of the main arm will rotate one of said spools in one direction, and other means operating in connection with a printing tape wound on one of said spools to reverse the movement thereof.

In testimony that I claim the foregoing as my invention I have signed my name in presence of the subscribing witnesses this 30 11th day of June 1915.

HORACE L. FREEMAN.
